2,036,842

PROCESS OF MAKING INSOLES

John Joseph White, Chicago, Ill., assignor to The
Florsheim Shoe Company, Chicago, Ill., a cor-
poration of Illinois

Application December 14, 1932, Serial No. 647,126

2 Claims. (Cl. 12—146)

This invention relates to shoe construction and particularly to the manufacture of welt shoes.

As a result of the process of manufacture of welt shoes heretofore practiced, the marginal portions of the insole, after being subject to a slight amount of use, curl and cause the feather edges of the insole to produce annoying protuberances or ridges, which cause the shoe to often times wear unduly at one side and form callouses and the like on the foot of the wearer. The shoe when in this condition causes considerable discomfort to the wearer, and after a short period of use necessitates discarding early in the life of the shoe.

15 To overcome disadvantages inherent in prior manufacture of welt shoes is accordingly the principal object of this invention.

A further object of the invention is to construct a shoe in which the feather is removed from the insole.

20 It is another object of the invention to provide a featherless insole having a flange formed to space the insole from the outsole for receiving filling material, and providing a support for the insole such that the latter will not sway or run over on one side.

It is another object of the invention to provide a shoe construction including an insole which will not curl or wrinkle at its edges.

25 In accordance with the general features of the invention, the insole is formed on its upper side throughout the entire margin thereof except for the heel, with a rabbet providing a ledge forming a continuation of the bottom of the insole. A 30 channel is formed in the bottom of the insole adjacent said ledge, leaving a lip in substantial parallelism therewith, and the upper and welt are secured to the rabbeted edge of the insole by means of stitching through the bottom of the 35 channel. When the welt is turned into substantial parallelism with the plane of the insole, the ledge and lip extend downwardly from the insole and are cut away in the plane of the lower surface of the welt. This plane is somewhat be- 40 low the plane of the lower surface of the insole, and the parts rest on and are secured to the outsole by stitching through the welt as is usual in the manufacture of welt shoes. The space thus enclosed receives waterproofing filler ma- 45 terial which serves to prevent caving in of the insole and yet provides flexibility, and also prevents squeaking between the insole and outsole.

50 With this construction, the secured margin of the upper does not underlie the marginal portions of the insole so that the upper cannot cause

the margins of the insole to be curled. The rabbet is such that the edge of the insole is undercut and when the insole, upper and welt strip are stitched together, the upper extends along the undercut edge and extends laterally away from the insole to avoid abruptness. Thus substantially the entire insole constitutes a tread for the foot of the wearer, so that curling up of the margin of the insole around the foot is precluded.

Other objects and advantages of the invention will appear as the description proceeds.

This invention (in a preferred form) is illustrated in the drawing and hereinafter more fully described.

On the drawing:

Figure 1 is a schematic bottom view of an insole together with portions of the upper and welt of a shoe, illustrating at different portions thereof of the condition at the conclusion of various steps in the manufacture of a shoe in accordance with the present invention.

Figures 2 to 6 inclusive are enlarged fragmentary sectional views as at A to E inclusive respectively in Figure 1, showing an insole right side up, however, with an edge thereof in successive stages of manufacture; Figures 3, 4, 5, and 6 showing also the manner in which the upper and welt are applied to the insole.

Figure 7 is a fragmentary transverse sectional view of a shoe constructed in accordance with the principles of this invention.

As shown on the drawing:

Referring now more particularly to the drawing, the insole 1 formed in accordance with the principles of the present invention is blanked out 35 and formed in its bottom surface 2 with a marginal outwardly extending channel 3, leaving a lip 4 which is notched at 5 to separate the heel portions of the lip from the remainder 6 of the lip. The upper surface 7 of the insole is formed 40 at the margin thereof with a rabbet 8, leaving the edge surface adjacent the rabbet undercut as shown at 9. The ledge 10 forming the bottom of the rabbet 8 is thereupon turned down as shown at 11 in Figure 3.

The lower margin 12 of the upper 13 is thereupon placed with its lining 14 adjacent the ledge 10 and inclined edge 9, and the strip of welt 15 arranged vertically against the outer surface of the upper 13 and with its stitching groove 16 50 outermost and at substantially the elevation of the juncture 17 between the inclined face 9 and the ledge 10. With the parts thus arranged, they are stitched together by the thread 18, the parts assuming the shape and relationship shown in 55

Figure 4. The welt strip 15 is then turned into a plane substantially parallel with the plane of the insole 1, with the parts then occupying the relationship shown in Figure 5. The lower surface 19 of the welt strip 15 is now lower than the bottom 2 of the insole 1, and portions of the lip 6, ledge 10 and upper 13 extend even below the said lower surface 19. The portions thus extending are trimmed even with said lower surface 19 as shown in Figure 6, the channel formed by the lower surface 2 of the insole 1 and the stump 6a of what was formerly the lip 6 is filled. The groove 21 formed by the stump 6a and the stump 10a may if desired also be filled 15 with the filling material 20. The outsole 22 is thereupon stitched at 23 to the welt 15, thereby completing the formation of the sole of the shoe. During this stitching operation, the upper surface 10 of the welt 15 is trimmed as at 24.

It will be appreciated from the foregoing that with this construction there is substantially no overlapping of the margin of the insole with respect to the attached portion of the upper, so that the constant upward pull on the upper, during wear of the shoe, cannot result in curling up of the margin of the insole and the consequent formation of annoying ridges, wrinkles and the like. By bevelling the upper portion of the edge of the insole, moreover, a substantially smooth or unridged juncture is afforded at 25 between the insole and the upper, thereby increasing further the comfort of the shoe thus constructed. In addition, the portions 6a and 10a together constitute a downwardly extending 30 flange which serves to space the remainder of the insole from the outsole so that waterproof filling material may be received in the space thus provided. In addition to the waterproofing and adhesive character of the filling material 20, this material is resilient and thus affords further 35 comfort for the wearer.

The construction above described is obviously quite simple, and is such that it may be made at no greater cost than the ordinary welt shoe and yet embodies a tread foundation which is level and smooth and which will remain in this condition throughout substantially the life of the shoe. Moreover, the adoption of the foregoing

method of manufacture may be effected without reorganization of present and known types of welt shoe manufacturing machines, and is well adapted for commercial production.

It will be observed that the flange formed by the stumps 6a and 10a is of substantial girth so that it serves not only to properly space the insole from the outsole but also to prevent the insole from swaying or creeping or treading over to one side and getting out of shape. 10

I am aware that many changes may be made and numerous details of construction may be varied through a wide range without departing from the principles of this invention, and I, therefore, do not purpose limiting the patent granted 15 hereon otherwise than necessitated by the prior art.

I claim as my invention:

1. The process of making an insole having a supporting flange for providing a substantially unyielding foundation for the insole, comprising the steps of rabbeting the upper margin of an insole blank so as to provide a peripheral ledge of substantial thickness relative to its width, bending the ledge downwardly so as to project below the lower surface of the blank, forming a stitching channel in the lower side of the blank so as to terminate transversely at substantially the same level as the corner of the rabbet to provide therebetween a stitching-in portion, bending the channel lip down alongside the ledge, and trimming said ledge and lip in a plane below the lower surface of the blank so that the ledge and lip together provide a means for proping and spacing the remainder of the insole from the outsole. 20

2. A process of forming a marginal portion of a shoe insole for connection to an upper and a welt, which consists in channeling the under marginal portion of the insole to provide a free lip, rabbeting the outer edge of the insole to provide a reduced margin, bending both the lip and reduced margin downwardly to form a cross-sectionally arched support for the insole and trimming the bottoms of the lip and ledge flat 40 so that they may be flush with the bottom of the upper and welt. 45

JOHN JOSEPH WHITE.
